UNITED STATES PATENT OFFICE.

JOHN J. FIECHTER, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

LIFTING DEVICE.

Application filed May 3, 1922. Serial No. 558,286.

My invention relates to improvements in lifting devices and has to do, more particularly, with a device adapted for lifting automobile bodies very quickly and easily from a supporting conveyor, carriage, or stand, so as to enable them to be moved from one place to another by an overhead conveyor system.

The principal object of my invention is to provide a device which is adapted to be suspended from an overhead support, such as an overhead conveyor, by means of which by a single manipulation of an operating handle or lever, the article may be lifted vertically and supported and retained in this lifted position.

In the manufacture of automobile bodies, the bodies are carried through certain stages of manufacturing operations upon conveyor belts or chains from which they are transferred to movable carriages or stands on which some of the remaining operations are performed. It has been customary heretofore to use an overhead conveyor system and a chain hoist for lifting a body from the conveyor belt or chain so that it might be transferred by the overhead conveyor system to the carriage or stand to which it was then lowered. This has required the labor of two men, one to manipulate the hoist to lift the body, and the other to steady the body while being lifted.

A leading object of my invention is to provide a lifting device adapted to be suspended from an overhead support, such as an overhead conveyor, and which may be manipulated by one hand of the operator to lift the structure, for instance, an automobile body, while the operator steadies the structure with his other hand. This eliminates the labor of one man and results in a corresponding saving in the cost of manufacture.

A further object of my invention is to provide a lifting device comprising a suspended lever which may be moved from one position to another to lift the load and which may be automatically retained in lifted position by the weight of the load. Another object of my invention is to provide a lifting device including a lifting lever and means for limiting the movement of the lever in a lifting direction at such a

point that the load automatically retains the lever in lifted position. 55

Further objects, and objects relating to details and economies of construction and operation, will definitely appear from the detailed description to follow. In one instance, I accomplish the objects of my invention by the devices and means described in the following specification. My invention is clearly defined and pointed out in the appended claims. A structure constituting a preferred embodiment of my invention is 60 illustrated in the accompanying drawings, forming a part of this specification, in which:

Fig. 1 is a view in side elevation of an automobile body showing my improved lifting device applied for lifting the body, and, 70

Fig. 2 is a view of my device in front elevation, said view being taken on the line 2-2 of Fig. 1.

In the drawing, the same reference numerals refer to the same parts throughout the several views and the sectional view is taken looking in the direction of the arrows at the ends of the section line. 75

In general, my invention consists in a lever which is fulcrumed intermediate its ends about a movable support. One end of the lever constitutes an operating handle and the other carries suitable means for engaging the body or part to be lifted. 80 Means are provided for limiting the swing of the lever in the lifting direction and I prefer to so position such means that in the limiting position of the lever, the load tends to retain the lever in such position. I may 85 suspend the lever by a linkage arrangement comprising a yoke pivotally connected to the support and a pair of links connecting the ends of the yoke with spaced points on the lever. I may cause the end of the lever to 90 engage the yoke to limit the movement of the lever in the lifting direction. 95

In the drawings, I have illustrated a device for lifting the automobile body, 10, for instance, from a stand, 11. This device 100 is suspended from the supporting member, 12, suspended from an overhead carrier, such as an overhead conveyor system. A cross bar, 13, carries a pair of hooks, 14, which are adapted to engage suitable portions or openings in the body, 10, so that, 105

when the cross bar, 13, is lifted, the body is lifted from the stand, 11. A cross yoke, 15, is pivotally connected intermediate its ends to the lower end of the supporting member, 12, and links, 16 and 22, are pivotally connected as at 17 and 21, to the ends of the yoke, 15. A lever, 19, is provided with an operating handle, 20, at one end, and means are provided at the other end of the lever to engage and lift the bar, 13, and with it the load to be lifted when the lever is rocked. Any suitable engaging means may be employed for this purpose. In the drawings I have shown a simple illustrative means comprising a hook, 25, pivotally connected to the end of the lever, as at 24, and provided with a finger, 26, adapted to engage the bar, 13. The lower ends of the links, 16 and 22, are pivotally connected to lever, 19, at the points, 18 and 23, spaced from each other.

In Fig. 2, the device is shown in full lines in its lowered position, and in dotted lines in raised position. When the operator grasps the handle, 20, and swings it downwardly, the linkage is moved so as to lift the point, 24, and, consequently, the hook, 25, which carries the bar, 13, and the body, upwardly. This movement continues until the end of the lever, 19, strikes the yoke, 15, as shown in dotted lines in Fig. 2. In this position, the load acts downwardly along a line passing through the end of the lever, 19, and, as shown in dotted lines in Fig. 2, the load is exerted so as to tend to swing the handle, 20, of the lever, 19, further to the left. It is to be noticed that the handle, 20, of the lever, 19, has been moved from the position shown at the right hand side of Fig. 2. This movement of the lever, 19, serves to swing the yoke, 15, on its pivot and lifts the point, 24, at which the load is applied to the lever, 19. This movement of the lever, 19, in the lifting direction, is limited because the end, 24, of the lever, strikes the yoke, 15, since both the lever and the yoke move in the same plane. The point at which the end of the lever engages the yoke, 15, is so located that the reaction of the load on this system of links and levers tends to continue the movement of the lever, 19, in the lifting direction, but such movement is prevented by the engagement between the end of the lever and the yoke, 15. Therefore, this arrangement serves not only to limit the throw of the lever in the lifting direction but also to retain the lever automatically in this limiting position. This is of considerable importance from the practical standpoint, since it enables one man to operate this lifting device and, at the same time, to control the body or other load which is lifted by it. The operator grasps the handle, 20, with one hand and steadies the body with the other. He swings the

lever, 19, through the arc indicated in Fig. 2 of the drawings until it reaches its limiting position, in which it will be automatically retained. Thereafter, the operator can give his entire attention to moving the body from one place to the other by means of the overhead conveyor system. The load can be lowered by simply rocking the lever, 19, in reverse direction. It will be seen that this device is very simple in its nature but automatic in its locking action so that the mere throwing of the lever in a lifting direction to its limit of movement locks the lever, so as to hold the load in lifted position.

I am aware that the lifting device disclosed in this specification may be altered considerably without departing from the spirit of my invention and, therefore, I claim my invention broadly, as indicated by the appended claims. 85

Having thus described my invention, what I claim as new and useful and desire to secure by Letters Patent is:

1. A device of the class described comprising a lever, a member secured to one end of said lever for engaging the load to be lifted, and means for fulcruming said lever including a yoke pivotally connected to a relatively fixed support and a pair of links pivotally connected to said yoke and to spaced points on said lever.

2. A device of the class described comprising a lever, a member connected to one end of said lever for engaging the load to be lifted, and means for fulcrumming said lever including a yoke pivotally connected to a relatively fixed support and a pair of links pivotally connected to said yoke and to spaced points on said lever, one end of said lever being adapted to engage said yoke to limit movement of the lever in the lifting direction. 100 105

3. A device of the class described comprising a lever, a member connected to one end of said lever for engaging the load to be lifted, and means for fulcruming said lever including a yoke pivotally connected to a relatively fixed support and a pair of links pivotally connected to said yoke and to spaced points on said lever, one end of said lever being adapted to engage said yoke, to limit movement of the lever in the lifting direction, at a point such that the weight of the part to be lifted tends to continue the movement of the lever in the lifting direction.

4. A device of the class described comprising a yoke pivoted on a relatively fixed point of support, a pair of links connected to the ends of said yoke, a lever connected to the lower ends of said links, and a lifting hook carried by one end of said lever.

5. In a lifting device of the character described, a lever having means at one end to 130

- engage the load to be lifted, a movable suspended fulcrum for said lever, whereby when said lever is rocked about its fulcrum, the vertical dead center line of the load is 5 permitted to move beyond the vertical line through said fulcrum, and means to arrest said lever when the last-mentioned line is passed.
6. A lifting device comprising a member 10 pivotally suspended from an overhead support, and a lifting lever pivotally suspended intermediate its ends from said member, and having means at one end to engage the load to be lifted, said lever arranged to rock in 15 lifting direction whereby to carry the point of connection of the load engaging means beyond the vertical line of the fulcrum point of suspension of said pivotally suspended member.
- 20 7. A device of the class described comprising an over-head support, a lever having means at one end thereof for engagement with work to be lifted into raised position, and a system of linkages interconnecting 25 said support and said lever whereby upon movement of said lever into work-raising position the lever will be automatically maintained in said position.
8. A device of the class described comprising a support, a lever carried on said support by an interconnecting system of relatively movable linkages, and having means at one end adapted to lift the work into 30 raised position, and means on said lever 35 adapted to abut one of said linkages when the lever is operated to raise the work, the work tending through its own weight to maintain said engagement.
9. A device of the class described comprising a relatively fixed support, a plurality of interconnected links pivotally mounted on said support, certain of said links having the ends thereof freely disposed, and a lever connected to said freely disposed ends at spaced points thereof whereby to effect 45 the completion of a lazy-tongs linkage.
10. A device of the class described, a support, a plurality of interconnected links pivotally mounted on said support, certain 50 of said links having the ends thereof freely disposed, a lever connected at spaced points thereof to said freely disposed ends, said lever having portions thereof projecting on either side of said spaced points, one of said portions constituting a support for the work 55 engaging means and the other of said portions constituting the operating handle for the lazy-tongs linkage.
11. A device of the class described comprising a support, a plurality of interconnecting linkages mounted on said support and providing at the free ends thereof relatively movable supports, and a lever having work engaging means at one end thereof secured to said relatively movable supports 60 whereby upon movement of said lever about said supports said work engaging means will be lifted into raised position.

In testimony whereof, I affix my signature.

JOHN J. FIECHTER.
